UNITED STATES PATENT OFFICE.

LESTER V. SIRCY, OF LOS ANGELES, CALIFORNIA.

LIFE BOAT FOR AEROPLANES.

Application filed November 14, 1927. Serial No. 233,147.

My invention is a life boat for aeroplanes.

An object of my invention is to construct an aeroplane with part of the fuselage of such design that it may be used as a life boat should the aeroplane, under necessity, alight on the water.

A more detailed object of my invention is the construction of a fuselage with the upper part of the tail of such construction that it may be utilized as a life boat and detached from the main body of the fuselage to carry the crew of the aeroplane. In this connection a detailed object of my invention is forming the boat like construction and carrying same in an inverted position, that is, with the bottom up, and arranging the construction so that it may be readily disconnected from the main portion of the fuselage and turned right side up in launching.

In constructing my invention I utilize a typical form of aeroplane, such as the land machine type, and preferably a machine having a cabin for the crew and for the passengers, if any. The tail portion of the fuselage, preferably from slightly forward of the trailing edge of the wings to a position adjacent the rudder, comprises a boat like structure, the under surface of the boat conforming to the upper surface of the fuselage. The boat structure is thus carried inverted and, on the deck, has oars, a mast, a sail and rudder securely lashed. The boat structure is also provided with compartments in which the passengers and crew may sit and has water-tight storage compartments for food, water, and other supplies.

The boat is constructed so that the bow end is held adjacent the stern or rudders of the aeroplane, whereas the stern of the boat is supported and latched adjacent the wings. The bow is held in position by a pivot stud, and the stern part of the boat is retained in position by latches, there being springs which are compressed so that on releasing of the springs, the springs elevate the boat structure so that it may be readily launched. The roof of the forward part of the fuselage over the cabin is provided with an opening so that the crew and passengers may readily escape and take to the boat.

My invention is illustrated in the accompanying drawings, in which a relatively small sized boat structure is shown:

Figure 1 is a side elevation of an aeroplane with my life boat incorporated therein.

Fig. 2 is a plan view.

Fig. 3 is a longitudinal section on the line 3—3 of Fig. 2 in the direction of the arrows.

Fig. 4 is a plan view of the boat removed from the aeroplane.

Fig. 5 is a vertical transverse section through the boat on the line 5—5 of Fig. 4 in the direction of the arrows.

Fig. 6 is a vertical section through the aeroplane substantially on the line 6—6 of Fig. 3 looking towards the stern.

My invention is applied to an aeroplane of the conventional type in which the fuselage in general is designated by the numeral 11, having a forward cabin section 12, and a tail section 13. The machine is provided with the usual chassis 14 with the wings 15, horizontal fin 16, vertical fin 17 and horizontal rudder 18 and vertical rudder 19.

The tail portion of the fuselage has the walls terminating substantially on a line 20 and at the front end also has a termination 21, which may have a partition, and has a vertical termination line 22 adjacent the rudders. In the space bounded by the lines 20, 21 and 22, there is positioned the life boat designated generally by the numeral 23.

This boat is illustrated more particularly in Figs. 3 through 6, in which the bottom 24 of the boat forms the top of the tail portion of the fuselage, and the deck 25 of the boat forms the horizontal roof above the tail portion of the fuselage. The boat has preferably a square bow 25' and a square stern 26. The boat structure is held in position by means of a pair of latch bolts 27 which are slidably mounted on the main portion of the fuselage, being preferably mounted on a relatively heavy cross beam 28, these bolts engaging in sockets 29 on the bottom of the boat structure.

A pair or more of relatively powerful compression springs 30 are mounted on a shelf 31 secured to the cabin part of the fuselage and preferably to a partition 32. These springs thrust upwardly on the deck of the boat. The bow of the boat has a pivot stud 33 which is received in a socket 34 on the tail portion of the aeroplane adjacent the fins and rudders. The top of the cabin or wings has an opening 35 which may be covered or not by a trap door as desired, through which the crew of the plane and the passengers may escape when landing on water, and detach the boat.

The boat structure in detail has an eye

36 adjacent the bow to which may be attached a cable 37 for mooring the boat to the aeroplane, and has a mast step 38 in the form of a tube extending from the bottom 5 of the boat through the deck. A partition 39' forms the whole forward part of the boat into a water-tight chamber, and back of this chamber there is a forward and a rear cock-pit 39 and 40, each of which has 10 sides 41 facing towards the bow, the partition 39' having a horizontal section 42 to accommodate the knees of the persons occupying the seat in the cock-pit.

Forward of the cock-pit 40 there is also 15 a partition 43 similar to the partition 39' and also having a horizontal section to accommodate the knees of the persons in such cock-pit. The cock-pits are provided with a curtain 44 which may be drawn tight 20 around the persons sitting therein and thus keep the water out.

Conveniently positioned in regard to the cock-pits there are a series of tanks 45 with 25 tightly fitting covers 46, these tanks being suitable for storage of provisions such as eatables, water, clothing, etc.; and at the stern of the boat I provide a rudder post tube 47 extending from the bottom through to the deck.

30 In order to navigate the boat I provide a mast 48, a pair of oars 49, a rudder 50, this having a rudder post 51 and tiller 52. These articles are clamped in place by lashings 53, 54 and 55. The rudder is inserted 35 by detaching the tiller and thrusting the rudder post down through the pipe 47 after the boat has been sprung up by the springs 30; or if there is not time for this, the rudder can be shipped after the boat is in the water, by reaching over the stern. A sail 56 is held in place by lashings 57.

The manner of using and launching the boat is substantially as follows:

Presuming that the crew have warning 45 of a forced landing on the water, just before such landing one of the members of the crew can, if desired, pull the latched bolts 27 so that the boat will be elevated at the stern by the springs 30; or if desired 50 this may be done after the plane lands on the water and is floating on the fuselage, the pivot stud 33 in this action holding the bow of the boat at the tail end of the aeroplane. When the crew and passengers are ready to 55 leave the aeroplane, they can get out of the cabin through the opening or hatchway 35 and then by taking hold of one side of the boat they can tilt it over so that it is inverted, that is, so that it lands in the water 60 with the deck up and the bottom down. The crew and the passengers may then embark in the boat and cut this loose from the aeroplane, if this shows signs of sinking, or if they wish to leave it.

65 The sail, rudder and oars provide means

for propulsion and it is understood that one of the storage compartments would be provided with navigating instruments. The boat, as above mentioned, has a number of water-tight compartments and as the tanks 70 for provisions are made water-tight, there is no particular danger of the provisions being damaged by water.

Various changes may be made in the principles of my invention without departing 75 from the spirit thereof, as set forth in the description, drawing and claims.

I claim:

1. In an aeroplane, the combination of a fuselage, a detachable boat structure built 80 into the top of the fuselage, the bottom of the boat forming the top of the fuselage, means to retain the boat structure in locked position in reference to the main body of the fuselage, and means on unlocking to raise one end of 85 the boat whereby the boat may be detached from the fuselage structure.

2. In an aeroplane, the combination of a fuselage, a boat structure built into the upper 90 part of the fuselage, one part of the boat forming the top of the fuselage, the boat having a pivotal connection at one end to one part of the fuselage, means to latch the other end to another part of the fuselage, and means on releasing of said latches to partly elevate the 95 boat.

3. In an aeroplane, the combination of a fuselage having a boat structure built into the top thereof, the bottom of the boat forming 100 the top of the fuselage, one end of the boat being pivotally connected to one end of the fuselage, the other end of the boat being retained by latches, and means on releasing of the latches to raise the end of the boat held 105 thereby.

4. In an aeroplane, the combination of a fuselage, a detachable boat structure built therein, part of the boat forming the top of the fuselage and the sides of the boat forming part of the sides of the fuselage, means 110 to retain the boat in position on the main body of the fuselage, and means to partly raise one end of the boat to facilitate launching and detaching of the boat from the fuselage.

5. In an aeroplane, the combination of a 115 fuselage having a boat structure mounted therein and forming part of the fuselage, the bottom of the boat forming the top of the fuselage and the bow of the boat being adjacent the rear end of the fuselage, means to retain the bow end by a pivotal connection, latches to retain the stern end of the boat, and springs on releasing of the latches to lift the stern end of the boat.

6. In an aeroplane, the combination of a 125 fuselage having a boat structure built under the upper part thereof, the bottom of the boat forming the top of the fuselage, the deck of the boat having navigation equipment mounted thereon, means to retain the boat in 130

position on the main part of the fuselage, and spring means to elevate part of the boat to facilitate launching.

7. In an aeroplane, as claimed in claim 6, one end of the boat being connected by a stud and socket connection with one end of the fuselage, the other end of the boat being retained by a latching means, said boat being tilttable when elevated, utilizing the pin and socket as a pintle for overturning.

8. In an aeroplane, the combination of a fuselage having a boat structure built therein, the bottom of the boat forming the top of the fuselage, said boat having water-tight compartments and cock-pits for the crew, navigation equipment secured to the deck of the boat, means to attach the boat to the main part of the fuselage, and means to partly

elevate one part of the boat to facilitate launching.

9. In an aeroplane, the combination of a fuselage, a boat structure built therein, the bottom of the boat forming the top of the fuselage, and the sides of the boat part of the sides of the fuselage, the bow of the boat being positioned adjacent the rear of the fuselage, a latching means holding the stern of the boat adjacent the wings of the aeroplane, a spring interconnected between the boat structure and the main portion of the fuselage to partly elevate the boat on a release of said latches.

In testimony whereof I have signed my name to this specification.

L. V. SIRCY.
